UNITED STATES PATENT OFFICE

JACK L. GOODSPEED, OF SEATTLE, WASHINGTON, ASSIGNOR TO PRESCOTT IRON WORKS,
OF SEATTLE, WASHINGTON

TRIM-SAW LIFT UNIT

Application filed October 29, 1928. Serial No. 315,812.

This invention relates to trim saw lift units as employed with lumber trimmers of that character used in sawmills for cutting lumber in uniform, standard lengths; such trimmers including a plurality of swingingly suspended saws that are independently adjustable into and from the path of the lumber to be trimmed as it is advanced by a conveyer mechanism across the trimmer table.

10 It is the principal object of this invention to provide a mechanically operated device whereby a saw may be lowered quickly to trimming position without undue jar and may likewise be raised clear of the lumber after trimming has been done; the mechanism operating automatically at the completion of both the lowering and lifting movements to disconnect the saw lifting and lowering member from its driving element, so that the saw will remain at either position of adjustment until the operator, by manipulation of a certain control device, restores the driving connection to again set the unit in operation.

25 More specifically, the invention resides in the provision of a lift unit employing in combination with a continuously driven gear, a yoke from which the saw is suspended and which includes rack bars disposed at opposite sides of the gear and which, by lateral shifting of the yoke, may be selectively engaged with the gear to cause the yoke to be raised or lowered; the mechanism also including means for disconnecting the yoke from the gear at the completion of a lowering or raising adjustment.

30 Other objects of the invention reside in the various details of construction and in the combination of parts and in their mode of operation, as is hereinafter described.

40 In accomplishing these and other objects, I have provided the improved details of construction, the preferred forms of which are illustrated in the accompanying drawings, wherein—

45 Figure 1 is a side elevation of a trim saw lift unit embodying the present invention; the saw being shown in raised position.

50 Figure 2 is an enlarged side view of the saw raising and lowering mechanism, shown in raised position.

Figure 3 is a similar view with the mechanism in lowered position.

Figure 4 is a horizontal cross section taken substantially on the line 4—4 in Figure 2.

Figure 5 is an enlarged detail view illustrating the relative position of the latch mechanism and control levers, when the unit is supported in raised position.

Figure 6 is a similar view showing relative position of parts when the yoke is released for lowering the saw.

Figure 7 is another view, illustrating the release of the yoke retaining latch for permitting lateral movement of the yoke preceding raising the saw.

Referring more in detail to the drawings—

In Figure 1, 1 designates the supporting frame structure of a trimmer table having an upwardly inclined top and having a revolubly driven shaft 2 along its upper edge equipped with suitable sprocket wheels, as at 3, about which conveyer chains 4 operate to advance the boards 5 beneath the trimming saws. Adjacent the table is a vertical frame structure comprising, in part, a horizontal beam 6 to which a plurality of saw ladders 7 are pivotally attached. In the present instance, the ladder is swingingly pivoted at one end on a revolubly driven line shaft 8 that is supported from the beam 6 so that the outer end of the ladder may swing in a vertical plane from and toward the trimmer table. At its outer end, the saw ladder is equipped with an arbor 9 whereon a circular saw 10 is mounted; the saw being driven by a sprocket chain belt 11 operating about suitable sprockets fixed, respectively, on the arbor 9 and on the shaft 8.

In the present trimmer, the several saw ladders (only one being shown) are each raised and lowered by individual mechanisms supported above the line of saws on a suitable frame including a horizontal beam 14 placed parallel with the beam 6, and the several mechanisms are operated from a rotatably driven line shaft 16 which may be supported in any suitable manner.

Each of the saw lifting and lowering units consists of a U-shaped yoke 18 mounted for vertical movement in a guide and supporting bracket that is fixedly mounted on the beam 100

14. In Figure 1, this bracket is designated in its entirety by reference numeral 19. A link 21 connects the lower end of the yoke with the outer end of the saw ladder 7 so that the latter and the saw carried thereby will be moved upwardly or downwardly in accordance with movement of the yoke.

10 The yoke 18 comprises the two parallel leg portions 18a and 18b connected across their lower ends by the cross piece 18c to which link 21 is attached, and across their upper ends are connected by a plate 23 that is attached thereto by bolts 24; there being compression springs 25 interposed between the 15 ends of the plate and nuts 24' on the bolts for absorbing shock incident to lowering.

20 The guide bracket 19, within which the yoke is slidably contained, comprises opposite side plates 19a and 19b that are disposed in parallel, spaced relation and provided with aligned openings 27 through which the shaft 16 extends. At their outer ends, the side plates are rigidly joined together by transversely disposed bolts 28 and, at their 25 inner ends, they are rigidly joined by an integral top web 30 and a base web 31 providing a vertical flange 32 which serves, with the horizontal web 31, as a seat whereby the bracket is mounted on the beam 14. Bolts 33 are extended through the beam and through 30 the flange 32 to secure the bracket in place.

25 Keyed on the shaft 16 between the side plates of the bracket 19, is a gear pinion 35 which revolves continuously in the same direction, and this is contained between the vertical rack bars 18a and 18b of the yoke 18. The yoke is vertically slidable within a carrier which, in turn, is horizontally shiftable within the bracket 19 for the purpose of shifting the yoke to bring one or the other of the rack bars into engagement with the gear 35. The carrier mentioned comprises opposite side plates 36-36' that are supported, respectively, just within the side 40 plates 19a and 19b of bracket 19; the supporting means consisting of pins 37 and 38 which are extended through the ends of the plates and also through horizontal slots 39 that are provided therefor in the side plates 45 of the bracket. These slots are of sufficient length as to permit of the necessary horizontal shifting of the carrier for bringing one or the other of the rack bars into contact with the gear when this is desired. The plates 50 36-36' are also provided centrally with elongated slots 40 through which the shaft 16 extends and which also receives therein the hub portions 41 of a pair of disks 42 that are disposed about the shaft closely adjacent the opposite sides of the gear 35. These 55 disks are circular and are of such diameter that they project upwardly above the top of the bracket 17 and serve by direct contact with the cross bar 23 as means for supporting the yoke 18 when in its lowered position.

60 Mounted on the pins 37 and 38, are rollers 45 which engage with the outside, vertical edges of the yoke and serve as guides for the latter as it moves between raised and lowered positions. When the yoke is in its raised position, it is supported by the end of a horizontally disposed latch bolt 49 that is slidably mounted between the side plates of the bracket upon one or more supporting elements 50. A roller 52, supported from the 65 bracket, overlies the bolt to retain it in place on elements 50 and a coiled spring 53 is fixed to a depending leg 49' at the outer end of the bolt and to a pin 54 fixed in the bracket side plate to yieldingly urge the bolt inwardly toward the yoke which is provided near its lower end with an offset providing a downwardly facing shoulder 55 for engaging the bolt as its means of support.

70 For drawing the bolt outwardly for releasing the yoke for downward travel, there is provided a lever 58 pivotally attached about midway between its ends to the bracket by a pivot pin 59. This lever is attached at its lower end by a pin and slot connection, as at 60, with the outer end of latch bolt 49 and, at its upper end, it projects somewhat above the top of the bracket and has operative connection, as at 61, with the outer end of a horizontally extended lever 62 (see Fig. 4) that is fixed to a pivot pin 63 mounted vertically in the bracket. An actuating lever 64 is fixed to the pin 63 and to this a pull cable 65 is connected. A coiled spring 66 is attached, under tension, to the lower end of the lever 58 and to the bracket to exert an inward pull on the lower end of the lever.

75 Shifting of the carrier frame from right to left, as from the dotted line position to the full line position as shown in Figure 3, is effected by the expansion of a coiled spring 70 that is retained under compression between an abutment 71 at one end of the carrier frame and an opposed abutment 72 at the outer end of the bracket. A retaining latch 75 is attached to the end of the carrier frame by a pivot pin 76 and this has a hook 77 at its end adapted to hook over a cross bar 78 between the bracket plates as a means of retaining the carrier frame at the position as 80 shown in Figure 2. Release of the latch to permit outward shifting of the carrier, is effected by the lifting contact with the hook of an inwardly extending latch tooth 80 mounted in the central portion of the lever 58. This latch tooth has limited outward travel and is urged outwardly by a spring 81 housed back of the tooth.

85 For purposes presently apparent, it will be noted that the gear toothed surface of the rack bar 18a terminates at a spaced distance from the upper and lower end of the bar so that when the yoke is at either its upper or at its lower position of travel, the gear will revolve free of the rack. It is also noted 90

that the toothed surface of the bar 18b extends practically the length of the bar and at the lower end of the rack it curves inwardly toward the rack bar 18a. The rack bars are so spaced that the gear can mesh with but one at a time.

With the parts so constructed, and assembled as described, the operation of the device is as follows:

Starting with the saw supported in raised position by the yoke 18 and link 21, as shown in Figure 1, and with the latch bolt 49 supporting the yoke, as shown in Figures 2 and 5, should it be desired to lower the saw, the operator first pulls outwardly on the cable 65 and thereby, through the action of levers 64, 62 and 58, causes the latch bolt 49 to be drawn outwardly and to be disengaged from supporting engagement with the shoulder 55 of the yoke. When the latch bolt is thus drawn out, the yoke is permitted to drop downwardly and, in so doing, the lower end of the toothed surface of the rack bar 18a comes in mesh with the downwardly rotating side of gear 35 which thereby governs the rate of lowering the saw so that it is not permitted to drop suddenly but is brought down easily. When the yoke reaches its lower limit of travel, as shown in dotted lines in Figure 2, it is stopped by contact of cross bar 23 at its upper end with the upper, peripheral surfaces of the disks 42. The jar of contact, when the cross bar engages the disks, is absorbed by the springs 25. As the yoke reaches its lowered position the toothed surface of the rack bar passes below the gear and the latter revolves freely.

When it is desired to raise the saw, the operator releases the pull on the cable 65 and the spring 66 operates to pull the lower end of the lever 58 inwardly and by this movement brings the latch tooth 80 up against the lower end of the hook end 77 of latch 75 and releases the hook from the cross piece 78, thereby permitting the spring 70 to expand and to push the carrier, in which the yoke is contained, outwardly so that the yoke moves from the dotted line position of Figure 3 to the full line position. This shifting of the yoke brings the teeth of the rack bar 18b into mesh with the gear 35 and the gear operates then to move the yoke upwardly and to thereby raise the saw. As the lower end portion of the rack bar 18b reaches the gear 35, the inward curve of the rack surface causes the yoke to be moved back to the right and final upward movement of the yoke brings the shoulder 55 above the line of the latch bolt 49 and the latter is snappcd beneath the shoulder 55 by the inward pull of the spring 53. Simultaneously with the inward movement of the latch bar, the latch 75 drops over the cross bar 78 and thus holds the carrier at the position shown in full lines in Figure 2.

When the yoke moves from its lowered to

its raised position, the gear 35 is automatically disconnected therefrom by running out of the lower end of the rack bar 18b and likewise, when the yoke moves from its raised to its lowered position, the gear is automatically disconnected from the rack 18a by running out from the upper end of the rack. Thus, the release of the driving connection between the yoke and the gear is made automatic for both the raising and lowering movements.

Having thus described my invention, what I claim as new therein and desire to secure by Letters Patent, is:

1. In a trim saw lift unit, a vertically disposed saw suspending yoke comprising vertical, spaced racks, a driven gear disposed within the yoke, a releasable means normally supporting the yoke in raised position, means for actuating said supporting means to release the yoke for downward travel and permit one of said racks to engage the gear for a controlled lowering of the saw, means for limiting downward travel of the yoke after the gear has left the rack, manually controlled means for shifting the yoke when in lowered position to engage the other of said racks with the gear for raising the saw.

2. In a trim saw lift unit, a vertically disposed saw suspending yoke comprising vertical, spaced racks, a driven gear disposed within the yoke, a releasable means normally supporting the yoke in raised position, means for actuating said supporting means to release the yoke and permit one of said racks to engage the gear for a controlled lowering of the saw, means for limiting downward travel of the yoke after the gear has left the rack, manually controlled means for shifting the yoke when in lowered position to engage the other of said racks with the gear for raising the saw and means for laterally shifting the yoke to effect disconnection of the gear from the racks at the end of the raising movement of the yoke.

3. In a trim saw lift unit, a fixedly mounted bracket comprising spaced apart side plates, a driven shaft extended transversely through the bracket, a gear keyed on the shaft between the side plates, a yoke carrier horizontally adjustable within the bracket, a saw suspending yoke vertically slidable in the carrier between raised and lowered positions for raising and lowering the saw; said yoke comprising vertical, spaced apart racks disposed at opposite sides of said gear, a latch bar engaged with the yoke for normally supporting it in raised position, means for shifting the bar to release the yoke to permit it to move downwardly and to thereby engage one of the racks with the gear for lowering the saw, means for supporting the yoke free of the gear when it reaches its lower limit of travel, means for shifting the carrier to move the yoke to engage the other rack with the gear for raising the saw.

4. In a trim saw lift unit, a fixedly mounted bracket comprising spaced apart side plates, a driven shaft extended transversely through the bracket, a gear keyed on the shaft between the side plates, a yoke carrier that is shiftable outwardly and inwardly within the bracket, a saw suspending yoke vertically slidable in the carrier between raised and lowered positions for raising and lowering the saw suspended thereby; said yoke comprising vertical, spaced apart racks disposed at opposite sides of said gear, a latch bar engaged with the yoke for supporting it when in its normal, raised position, means for drawing the latch bar to release the yoke for downward travel and to thereby engage one of the said racks with the gear for regulating the lowering of the saw, means for supporting the yoke free of the gear when it reaches its lower limit of travel, means for shifting the yoke carrier outwardly to thereby move the yoke and to cause the other rack to engage the gear for raising the yoke; said latter rack being directed at its lower end toward the opposite rack for the purpose of returning the carrier to normal position as the yoke again reaches its upper limit of travel.

5. A device as in claim 4, wherein a retaining latch is attached to the carrier and engageable with a part fixed in the bracket for holding the carrier in normal position inwardly of the bracket and a spring is mounted under compression between an abutment on the carrier and an abutment in the bracket for urging the carrier outwardly when said latch is released.

6. In a trim saw lift unit, a fixedly mounted bracket comprising spaced apart side plates, a driven shaft extended transversely through the bracket, a gear keyed on the shaft between the side plates, a yoke carrier shiftable outwardly and inwardly within the bracket, a saw suspending yoke vertically slidable in the carrier between raised and lowered positions for raising and lowering the saw suspended thereby; said yoke comprising vertical, spaced apart racks disposed at opposite sides of said gear, a yieldable latch bar engaged with the yoke for supporting it when in its normal, raised position, a pivoted release lever for shifting the latch bar to release the yoke for downward travel to thereby engage one of the racks with the gear for lowering the saw, means for stopping and supporting the yoke free of the gear when it reaches its lower limit of travel, a latch attached to the carrier and engageable with a part fixed in the bracket for retaining the carrier inwardly of the bracket, a spring mounted under compression between an abutment on the carrier and an abutment in the bracket for urging the carrier outwardly when said latch is released and a latch finger provided on said release lever engageable with the carrier latch to release the latter.

7. In a trim saw lift unit, a fixedly mounted bracket comprising spaced apart side plates having horizontally aligned slots therein, a yoke carrier mounted within the bracket, supporting pins for the carrier extended through said slots of the bracket and whereby inward and outward movement of the carrier is limited, rollers mounted on said pins at the ends of the carrier, a rotatably driven shaft extended through the bracket and carrier, the carrier having slots therein for receiving the shaft, a gear keyed on the shaft within the carrier, a saw suspending yoke mounted in the carrier between said rollers for vertical travel between raised and lowered positions; said yoke comprising spaced apart racks, means for normally holding the yoke in raised position, means for releasing the yoke from said means to bring one of said rack surfaces into mesh with the gear for lowering the saw, means for shifting the carrier when the yoke is in lowered position to engage the other rack with the gear for raising the saw and means for returning the carrier inwardly to normal position as the yoke reaches its raised position, and a releasable latch for normally retaining the carrier at its inner position.

Signed at Seattle, Washington, this 4th day of October, 1928.

JACK L. GOODSPEED.
